Lyman E. Dodge
ATTORNEY

UNITED STATES PATENT OFFICE

FRANK C. LA MAR, OF NEW YORK, N. Y., ASSIGNOR TO GREAT WESTERN FUSE COMPANY, OF NEW YORK, N. Y., A CORPORATION OF DELAWARE

FUSE CLIP LOCK

Application filed March 3, 1932. Serial No. 596,452.

This invention relates to a thermal electric fuse, particularly of the cartridge type, and more especially to a means for assuring the retention of such a fuse in clips and indicating the integrity thereof.

The ordinary and well known cartridge type fuse, used for the protection of electric circuits, is ordinarily positioned in clips, one at each end. These clips are ordinarily made 10 of spring material, and so formed as to retain the cartridge fuse in place therein by friction.

A continued and repeated removal and replacement of fuses in the clips, in time, so decreases their holding power that vibration or jarring may cause the cartridge fuse 15 to fall out.

A principal object of applicant's invention is the provision of a lock for application to the clips used for assuring the proper positioning and retaining of a cartridge fuse in 20 its clips.

A further object of the invention is the combination, with such a lock, of a means for indicating the integrity of the fuse.

25 Other objects and advantages will appear as the description of the particular physical embodiment selected to illustrate the invention progresses and the novel features will be particularly pointed out in the appended 30 claims.

In describing the particular physical embodiment selected to illustrate the invention, reference will be had to the accompanying drawing and the several views thereon, in 35 which like characters of reference will designate like parts throughout the several views, and in which:

Figure 1 is a front elevational view of a 40 pair of ordinary and well known cartridge fuse clips, a cartridge fuse in place therein, and a combined clip lock and fuse integrity indicator constructed in accordance with applicant's invention; Fig. 2 is a side elevational view, with some parts in section to 45 more clearly illustrate the construction, of the device as shown by Fig. 1; Fig. 3 is a top plan view of the device as shown by Fig. 1; Fig. 4 is a perspective exploded view of the locking finger members of applicant's invention; Fig. 5 is a side view of a modified

form of manually operable handle which may be used with applicant's invention; Fig. 6 is a fragmentary partial sectional view of the device as shown by Fig. 5.

Numeral 1 designates a support. This support is made of insulating material and generally is positioned vertically.

The support 1 is orificed, as at 2 and 3, for the reception of supporting means, such as bolts, as 4, which pass therethrough and through clips as 5 and 6. Nuts as 7, screw 60 threadingly engaged with a bolt, as 3, serve to firmly bind the clips to the support 1. The clips as 5, are commonly formed of a single strip of material which after being properly 65 slit is bent into a somewhat general U shape, as best shown in Fig. 3. The partially separated portions formed by slitting, such as 8, are bent inwardly, whereas the remaining portions of the legs of the U, as 9 and 10, are bent outwardly. The outwardly bent 70 portions are formed so as to substantially coincide with the portion of the peripheral surface of the end of the cartridge fuse which is to be inserted therein, while the bent 75 in portions 8 lie opposite the end of the cartridge fuse and thereby prevent endwise movement thereof, it being understood, of course, that the bent in portions 8 of each clip are placed remotely from the medial line between the clips, as best shown in Fig. 2.

All of the constructions hereinbefore described are old and well known.

A usual type of fuse used with the clips hereinbefore described is what is known as a 80 cartridge fuse which generally consists of an insulating tube 11 containing a thermal fuse 12 connected at each end to a metallic ferrule, as 13'. The metallic ferrules, as 85 13', are pushed into the clip from the open end thereof, forcing the legs apart until the ferrules rest within the curved out portions 9 and 10. When the fuse is in such position, if the clips, as 5, are in good condition, with plenty of spring tension therein, the cartridge fuse should be fairly well held, but if the clips are old, and if fuses have been 90 repeatedly inserted and removed therefrom, the spring tension of the clips will be so deteriorated that they are not sufficiently resili- 100

ent to properly retain the cartridge therein if subjected to violent vibration.

In order to properly retain the cartridge within the clips, even in spite of violent vibration, applicant has provided a combined clip lock and fuse integrity indicator.

Applicant's lock provides pairs of locking fingers, as 13 and 14, best shown in Fig. 3, which are adapted to contact with the outside of the prongs or legs of the U-shaped clip and force them together.

Applicant provides a pair of locking fingers for each clip. The locking fingers are provided with any appropriate means for drawing them together. In the particular form selected by applicant, each locking finger forms a prolongation of a locking finger member. These locking finger members are provided with means for drawing the locking fingers together and separating them, and with means for causing the fingers to be cooperatively related.

Locking finger 13, as best shown by Fig. 4, forms a prolongation of a plate 15 which has a struck-up portion 16 provided with an orifice 17.

Locking finger 14 forms a prolongation of a plate 18 formed with a struck-up portion 19 having a screw threaded orifice 20 therein. The plate 18 is also formed with bent over and under portions 21, 22, 23 and 24, as best shown in Fig. 4. These bent over and under portions, as 21 and 22, serve to receive and retain the plate 15 in close and slidable relation with the plate 18.

In order to slide one plate 15 relatively to another plate 18, applicant provides the handle bolt 25, best shown in Figs. 1 and 3. The bolt 25 has a manually operable handle 26 on one end thereof, passes through the struck-up portion 16 of plate 15, screw threadingly engages the struck-up portion 19 of plate 18, and is formed with sleeves 26' and 27, one on each side of the plate 18. This construction is such that a manipulation of the handle 26 causes a rotation of the threaded bolt 25 within the screw threaded orifice 20 of struck-up portion 19 of plate 18 and in accordance with the direction of rotation causes the plates 15 and 18 to slide one on the other so that the locking fingers, as 13 and 14 are either caused to approach or recede one from the other. When the locking fingers, as 13 and 14, are caused to approach, the legs of the U-shaped clip 5 are forced closer together and in closer contact with the cartridge fuse 11 so that it is thereby firmly held in the clips. If it is desired to remove the cartridge, then the locking fingers 13 and 14 are caused to recede one from the other to such an extent that they may be removed entirely from the clip, whereupon the cartridge fuse 11 may be removed and another put in place thereof, after which the locking fingers 13 and 14 are positioned again as shown in Fig. 3.

The near sides of plates 18 receive the ends of a fuse integrity indicator. In order to facilitate the reception and positioning of the ends of the fuse integrity indicator, applicant prefers to provide the near sides of the plate 18, as shown in Fig. 1, and in detail in Fig. 4, with upstanding portions 26" and with a screw threaded orifice 27. This construction permits the ends, as 28 and 29, of a fuse indicator 30 to be nicely positioned upon the near edges of the plates 18 and be attached to those plates by means of the headed screws, as 31.

The fuse integrity indicator may be of various forms. The essential requisite is that it shall include means exhibiting a distinctive indication that the fuse material 12 is destroyed. In the particular form shown by applicant, the fuse integrity indicator includes a lamp 32, preferably of the neon filled type, which becomes lighted when the thermal fuse becomes destroyed. One terminal of this lamp is connected, as by the wire 33, preferably through a resistance, as 34, to a metallic end ferrule 35. The other terminal of the lamp is connected, as by a conductor 36, preferably through a resistance, as 37, to another metallic end ferrule 38. Each of the end ferrules is firmly attached to the metallic extensions, as 28 and 29, which are secured in place, as hereinbefore described, by the screws as 31.

As a protection for the lamp 32 and resistances 34 and 37, and as a spacing means, applicant prefers to employ a non-conducting tube 41 surrounding the lamp 32 and fitting in the ferrules 35 and 38.

If the fuse material 12 of the cartridge fuse becomes severed, as by overloading, then the current flows through lamp 32 and causes it to glow, indicating that the cartridge fuse before which it is mounted is inoperative.

In Figs. 5 and 6 a modified form of manually operable handle is shown. This handle, designated as a whole by 42, may be made of any desired and appropriate material and includes an internal tooth member or gear 43. This member 43 may be made in any desired manner, but preferably, as an insert piece, and of metal.

On the bolt 25 a pinion 44 is positioned having teeth meshing with the internal gear 43. The handle member 42 is retained in place with its teeth in mesh with the teeth of the pinion 44 or in any appropriate manner, but preferably by forming the thread 45 on the end of the bolt 25 and engaging therewith an internal threaded nut 46.

The advantage of the modified manually operable handle 42 resides in the fact that if when the handles are moved to locking position as shown in Fig. 2 they do not come to a position in line and substantially parallel to the piece 11, then the nut 46 may be removed from the end of the bolt 25, the handle 42 re-

moved and rotated about the axis of the shaft 25 to a proper position, and then returned to place and the nut 46 put back. By such movement the manually operable handles as 5 46, corresponding to handles 26 of Figs. 1, 2 and 3, may be so placed upon the bolts 25 that they will assume the position as shown in Fig. 2 when the locking has been effected.

Applicant's device forms a unitary means 10 manipulative as a single device which may be placed in position upon the clips holding a cartridge fuse in place so as to assure the certain retention of the cartridge fuse in place, and at the same time indicate the integrity of the thermal fuse material within 15 the cartridge fuse.

Although I have particularly described one physical embodiment of my invention, and explained the principle, and construction thereof, nevertheless, I desire to have it understood that the form selected is merely illustrative but does not exhaust the possible physical embodiments of the idea of means underlying my invention.

25 What I claim as new and desire to secure by Letters Patent of the United States, is:

1. In a combined clip lock and fuse integrity indicator, in combination: two separated pairs of locking fingers adapted to contact with and press together the free ends of the legs of two separated substantially U-shaped fuse clips; means for causing the locking fingers to approach and/or recede one from the other and means associated with 35 said last named means for indicating the integrity of a fuse in the clips.

2. In a combined clip lock and fuse integrity indicator, in combination: two separated pairs of locking fingers adapted to contact with and press together the free ends of the legs of two separated substantially U-shaped fuse clips; means for causing the locking fingers to approach and/or recede one from the other; and an electric lamp including 40 two terminals, one of which is conductively connected to one of said pair of said locking fingers, and the other of which is conductively connected to the other of said pair of locking fingers whereby a destruction of a thermal element connecting the U-shaped clips causes the lamp to become 45 lighted.

50 3. In a clip lock, in combination: two separated locking fingers, adapted to contact with and press together the free ends of the legs of a substantially U-shaped fuse clip; two plates, one carrying one locking finger, and the other carrying the other locking finger; an upstanding projection formed with a 55 threaded orifice on one of said plates; an upstanding projection upon the other of said plates; a screw threaded bolt having its thread engaging the threaded orifice formed in the upstanding projection of the other plate; means to prevent said bolt from mov-

ing longitudinally relatively to the second mentioned upstanding projection; and means for causing said bolt to rotate whereby the locking fingers are caused to approach and/or recede one from the other.

4. In a combined clip lock and fuse integrity indicator, in combination: two separated pairs of locking fingers adapted to contact with and press together the free ends of the legs of two separated substantially U-shaped clips; means including a threaded bolt with a rotatively adjustable manually operable handle on one end thereof for causing the locking fingers to approach and/or recede one from the other.

5. In a clip lock, in combination: a threaded bolt for pressing together the free ends of the legs of two separated fuse clip portions; a manually operable handle on the bolt for manipulating the bolt, said bolt being provided with a plurality of projecting teeth and said manually operable handle being provided with corresponding projecting teeth whereby the bolt and handle may be engaged in various relative rotative positions; and means for holding the handle in position on the bolt.
